UNITED STATES PATENT OFFICE.

BRUNO VON BÜLTZINGSLÖWEN, OF NEW YORK, N. Y., ASSIGNOR OF ONE-HALF TO THEODOR SAUER, OF NEW YORK, N. Y.

MACHINE FOR FORMING HOOKS ON WIRE BALE-TIES.

SPECIFICATION forming part of Letters Patent No. 748,580, dated January 5, 1904.

Application filed April 21, 1903. Serial No. 153,678. (No model.)

To all whom it may concern:

Be it known that I, BRUNO VON BÜLTZINGSLÖWEN, a subject of the Emperor of Germany, residing at New York, in the county and State of New York, have invented certain new and useful Improvements in Machines for Forming Hooks on Wire Bale-Ties, of which the following is a specification.

These improvements relate to the same type of machines as described in my application, Serial No. 103,199, filed April 16, 1902, and are fully described in the following specification with reference to the accompanying drawings.

15 The main object of my present invention is to improve my aforesaid previous construction, so as to simplify and facilitate the different movements—that is to say, to provide means for automatically bending the wire—20 thereby facilitating the work formerly performed by the operator and for strictly confining the wire in place before and during the bending operation, so as to allow bending of even the strongest wire used in binding hay-bales.

Another important feature of my improved construction is the use of a coupling device which can be thrown into engagement by the least possible power and which results in a 30 tight hold of the coupled shafts, nevertheless allowing an easy and automatical disengagement of the same.

In the accompanying drawings, Figure 1 is a plan view of a machine embodying the aforesaid improvements. Fig. 2 is a plan view of the same, taken from underneath the base-plate. Fig. 3 is a front elevation of the machine, the base-plate being cut away, so as to expose all parts below the same. Figs. 4 and 40 5 are cross-sections on line 4 4 and 5 5, respectively, of Fig. 3. Fig. 6 is a detail front view of the principal parts of the hook-bending mechanism in inoperative position prior to the bending operation. Fig. 7 is a similar view showing the position of the parts at the completion of the bending operation, the bent wire being in place. Fig. 8 is a detail end view of the hook-bending mechanism. Fig. 45 9 is a detail cross-section of the same. Fig. 50 10 is a detail end view of the clamp device for gripping the ends of the bent hook dur-

ing the twisting operation, the wire ends being shown in section and all parts in their operative position. Fig. 11 is a detail plan view of the clamp device. Fig. 12 is a detail longitudinal section of the new coupling device. Figs. 13 and 14 are respectively a detail front view and plan view of the lever for bending the free end of the wire toward the long end of the wire body. Figs. 15 and 16 are respectively a detail front view and a plan view of the cam projection effecting the return movement of the main lever for the operation of the hook-bending mechanism, and Fig. 17 is a side view of a hook bent on my improved machine.

Similar letters of reference indicate corresponding parts throughout the drawings.

A represents the base-plate, supported so as to allow arrangement of mechanisms above and below the same. A rocking lever K is pivoted to a bracket *a* upon the base-plate, embracing with its upper forked end a sliding sleeve B upon the main shaft C, the latter being journaled in bearings *A'* and *A''*, upwardly projecting from the base-plate *A*. The forked end of lever K carries friction-rolls *h* in engagement with the projecting side flanges of sliding ring B, which is fastened to its shaft by spline connection. At 80 the left-hand flange of the sliding ring B, Fig. 3, three pivot-carrying ears *b* are provided, which by means of links *d* *f*⁴ *f*⁵ serve for operating the hook-bending mechanism. The latter comprises the following parts: 85 A circular head *C'* on the main shaft *C*, having lateral recesses *c* to receive two of the ears *b* of sliding sleeve B. A flattened head portion cast integrally with the forwardly-projecting plate *E*, on which the hook-bending mechanism is mounted, is screwed onto the circular head *C'*. A wire-bending lever *E*⁴, bent at a certain angle, so as to correspond with the shape of the hook, is laterally secured to arm *E*³, which is fastened upon a 90 pivot *e*⁵, journaled in the plate *E*. A pin *e'* projects eccentrically from the forward end of the pivot *e*⁵, while a pinion *E*², meshing with another pinion *E'*, is keyed on the opposite end of the same. The pinion *E'* is rotated by the sliding sleeve B through the medium of link *f*⁵ and crank *f*⁶. The hook-

bending lever F turns loosely upon a stud f' , projecting from the lower part of the plate E, and forces wire z round a pin e. A cam-surface f^3 of lever F operates a third lever E ^{5} , also pivoted to the plate E, against the tension of a leaf-spring e ^{2} . The left-hand upper end of lever F, Fig. 7, is provided with an upwardly-projecting support f^2 for lifting up the long end of the wire body z and securing both ends of the bent hook in proper position for the clamp device, which will be described later on. A link f^4 connects lever F with the sliding ring B.

The mechanism for tightly holding the bent hook in its position while the ends thereof are twisted around each other consists of a lock-plate D, sliding with its lower cut-out portion in a correspondingly-formed plate D', which is screwed upon the plate E. A cover-plate D ^{2} is fastened on plate D', overlapping the aforesaid cut-out portion, thus resulting in a tight hold of plate D, which may be shifted by the sliding sleeve B through link d. At the end of the plate E a spring-supported lock e ^{8} is provided, which keeps the long end of the wire body in a straight line during the operation of the hook-bending lever F. This lock e ^{8} is acted upon by a lateral projection e ^{6} of the wire-bending lever E ^{4} against the tension of a leaf-spring e ^{4} .

The clamp device for tightly gripping the wire ends during the twisting operation consists of a bracket A ^{3} , screwed upon the base-plate A, and a support-plate G, laterally projecting therefrom. The upper end of the bracket A ^{3} at its inner face possesses a die g, which forms in connection with a similar die g' on a rocking clamp-lever G ^{4} a proper support for the wire ends z. This rocking clamp-lever G ^{4} is pivoted to plate G and acted upon by a roller g ^{4} , journaled at the outer end of an oscillating double lever G', also pivoted upon plate G. A spring g ^{5} draws the rocking lever G ^{4} back to its normal position. The oscillating lever G' is turned upon its pivot, so as to act upon or release the clamp-lever G ^{4} , by means of a rod G ^{8} , sliding vertically upon its longitudinal recess g ^{6} , and an angular connecting-link G ^{2} . The rod G ^{8} projects through a suitable opening of base-plate A and carries at its lower end a lateral projection g ^{8} . The support-plate G has at its upper edge a groove g ^{9} as guiding means for correctly inserting the wires z, this groove g ^{9} being in a vertical plane with the dies g g' when they are in their operative position.

The means for automatically operating the hook-bending mechanism consists of the following parts: A bearing V is screwed underneath the base-plate A, carrying shaft S, to the forward end of which a disk N is fastened, being provided with several projections and cam-surfaces. A semicircular plate N', integrally cast with this disk N, lies in its inoperative position with its diametrical edge against the main lever K for operating the hook-bending mechanism. A bracket O, se-

cured underneath the base-plate A, has laterally-projecting guide-rails o, undercut, so as to tightly secure and guide a rod M, one end of which carrying a friction-roller m, lying against the main lever K, while to the other end an upwardly-projecting arm m' is laterally secured. The outer end n ^{2} of an abutment n rests just below this arm m' before the machine is started. Another semicircular cam N ^{2} is provided upon the periphery of disk N in such position as to operate the clamp device for securing the wire ends z during the twisting operation.

L indicates a bracket downwardly projecting from the base-plate A. Pivoted to the bracket are an angle-lever L' and a double lever L ^{3} , connected by means of a link L ^{2} and carrying at their free ends friction-rollers l and l', respectively.

The roll l rests upon the lateral projection g ^{8} of the vertical rod G ^{8} and depresses the latter against the tension of a spring g ^{X} when friction-roller l' is depressed by and running upon the cam N ^{2} .

The means for starting the machine comprise a foot-lever (not shown in the drawings) acting upon an angle-lever V ^{2} , which is fulcrumed at a bracket V', downwardly projecting from bearing V, and a coupling device of a simple yet very efficient construction. A cylindrical casing S' is mounted upon shaft S by a spline connection s ^{4} . This casing S' has a cut-out portion s', so as to allow insertion of a spiral spring s ^{3} , surrounding shaft S, while the inner end of this spring is supported at the end of boring s'. The movement of the spring in the opposite direction is limited by a ring S ^{3} , secured on shaft S. The flange S ^{2} of the casing S' has outwardly-projecting coupling-fingers s, which are in position to engage corresponding projections s ^{2} of bevel-gear P, loosely mounted on the rear end of shaft S. The left-hand flange of the casing S, Fig. 4, has a boring for a pin v, secured at the rear face of bearing V, thereby limiting the rotation of coupling S to just one revolution. The bevel-gear P meshes with a smaller gear P', secured on one end of a shaft U, which is journaled in a bearing U' under the base-plate A. The other end of this shaft carries a chain-wheel U ^{2} , which is operated by means of a chain and another chain-wheel I' from the main shaft C. The chain-wheel I' is secured upon the hub of a driving-pulley I, which is loosely mounted upon shaft C, the same coupling, as above described, being used for throwing this pulley into engagement with its shaft. The cylindrical casing H is mounted upon shaft C by a spline connection h'. A spiral spring h ^{2} , which is placed in the cut-out portion h, is limited in its movements by a ring H ^{3} , tightly secured upon shaft C. Coupling-fingers h ^{3} are provided at the end flange H ^{2} , so as to engage corresponding coupling-fingers h ^{4} , laterally projecting from the pulley I. The opposite end flange H' is acted upon by

80

125

130

a rocking lever K', which throws the coupling into engagement the moment the bending mechanism has finished a hook, this being effected by the following means: An abutment n' is screwed upon disk N in such position that during the rotation of the latter this abutment comes into contact with an angle-lever R', which rocks lever K' by means of a friction-roller R², thereby throwing the coupling on the main shaft into engagement. At the same time a pin k', laterally projecting from lever K' into a boring of a disk T', mounted upon an axle T, releases said disk, which starts to rotate on account of its connection with the main shaft C.

C² and T² represent chain-wheels in a ratio of one to three, thereby allowing three revolutions on the main shaft C during one revolution of axle T, the latter being mounted in bearings A⁴ A⁵ underneath the base-plate A. A bracket R, to which the angle-lever R' is pivoted, projects downwardly from the bearing A⁴, while the rod t is screwed into the bearing A⁵. A spring k² connects said rod t with the lower end of lever K'.

The operation of the machine is as follows: The pulley I may be operated by any suitable power whereby by means of the chain-wheel connection I' U² operation is transmitted to the bevel-gear P. On depressing the foot-lever, which is not shown in the drawings, this bevel-gear P is thrown into engagement with its axle S; but on account of the pin v and its corresponding recess in the coupling S' the operation will be limited to one revolution only. The wire z, which is placed in the machine in a position indicated in Figs. 3 and 6, is bent through the rotation of disk N. The moment the machine starts the cam N' actuates the main lever K, the lower part of which is pushed to the right to a position indicated in dotted lines in Fig. 3. During this progress the hook is bent and tightly kept in its position by lock-plate D. The heel f² of the hook-bending lever F has lifted the long end of the wire body so far as to bring it in close contact with the short end of the bent wire, thereby placing both in a proper position for the gripping device, which by means of the actuating-cam N² operates immediately after the hook is bent. While the hook-bending lever F performs its operation, the spring-supported lock e³ serves as abutment to keep the long end of the wire body in a straight horizontal line. This lock is, however, removed from the path of the bending-lever E⁴ by the projection e⁶ of the latter shifting the lock e³ back against the tension of its leaf-spring e⁴, so as to allow the wire to pass. As soon as the wire ends are tightly secured in the recess g g' the lever K' is turned upon its pivot by means of the lateral abutment n' of disk N, passing angle-lever R' and forcing the same into the dotted-line position of Fig. 3. The upper end of the lever K' throws thereby the coupling H into engagement with

the driving-pulley I, and as at the same time the pivot k' has released disk T' the latter starts to rotate in the ratio of the chain-wheels C² and T². After the abutment n' has passed angle-lever R' lever K' is kept in its position by pin k' sliding on the side of disk T' until one revolution of the same is completed, when, following the tension of spring k², lever K' locks disk T' and disengages the coupling H of the driving-pulley I. At the same time guide-rod M is horizontally shifted through the medium of the abutment n² striking the upwardly-projecting arm m'. The friction-roller m at the other end of the guide-rod M thereby draws back the main lever K to its normal position, whereby the finished hook is exposed, so as to be easily removed, the clamp device having released the ends of the same after the friction-roller l' of the oscillating lever L³ has slipped from the actuating-cam N² and under the tension of spring g³ all parts have returned to their inoperative position. At the same time the automatical coupling S is thrown out of engagement with the revolving bevel-gear P after one complete revolution, as pin v enters the boring in the side flange of the casing S'.

Having now fully described my invention, what I claim, and desire to secure by Letters Patent, is—

1. In a machine for forming hooks on wire bale-ties, the combination of means for automatically operating the hook-bending mechanism comprising a clutch-coupling, a suitable lever for operating said coupling, a shaft driven by said coupling, a disk secured on said shaft having a cam-surface, a rocking lever actuated by this cam, means actuated by said lever and operating the wire-bending mechanism, and means for returning said lever to its normal position and for stopping the rotation of the cam-carrying disk after a single revolution, substantially as set forth.

2. In a machine for forming hooks on wire bale-ties, the combination of a flattened head portion on the main shaft, an angular wire-bending lever journaled in said head portion and conforming in shape to the back part of the finished hook, a pinion keyed on the pivot of this bending-lever, a second pinion meshing therewith, a crank-and-link connection for operating said second pinion; a pin concentrically projecting from the end of the pivot around which the wire is bent; a hook-bending lever, fulcrumed on said head, having a heel to raise and support the wire body and a cam-surface; a third lever operated by said cam-surface and serving to deflect the front of the hook, and means for operating said hook-bending lever, substantially as described.

3. In a machine for forming hooks on wire bale-ties, the combination of a flattened head portion on the main shaft, an angular wire-bending lever journaled in said head portion and conforming in shape to the back part of

the finished hook, a pinion keyed on the pivot of this bending-lever, a second pinion meshing therewith, a crank-and-link connection for operating said second pinion, a pin concentrically projecting from the end of the pivot around which the wire is bent; a hook-bending lever, fulcrumed on said head, having a heel to raise and support the wire body and a cam-surface; a third lever operated by said cam-surface and serving to deflect the front of the hook and means for operating said hook-bending lever, a spring-supported lock on the end of the head serving as an abutment for the body of the wire in the hook-forming operation and pressed back by a lateral projection on the wire-bending lever, substantially as described.

4. In a machine for forming hooks on wire bale-ties, in combination with the main operating-lever K and its operating cam-disk N; the horizontally-guided rod M having a friction-roll m in bearing against said lever and an upwardly and laterally projecting arm m'; and a projection n, n² on said cam-disk acting on the arm m' to shift the sliding rod M and by means of the friction-roll m to restore the lever K to normal position, substantially as described.

5. In a machine for forming hooks on wire bale-ties, the combination with the wire-bending mechanism, of the sliding lock D, operating to hold the hook in position during the twisting operation, substantially as described.

6. In a machine for forming hooks on wire bale-ties, the combination with a cam-disk N and wire-bending mechanism operated thereby, of a gripping device comprising the fixed bracket A³ carrying the die g; the gripping-lever G⁴ carrying a corresponding die g', and the oscillating lever G' having a friction-roll g⁴ bearing against the lever G⁴ to impart this gripping movement thereto, and means operated by a cam-surface on the disk N to operate said oscillating lever, substantially as described.

7. In a machine for forming hooks on wire bale-ties, the combination with a cam-disk N and wire-bending mechanism operated thereby and a suitable gripping device for the wire; of the main shaft C carrying the hook-forming head E, a clutch-coupling to impart rotation to said shaft; means actuated by the disk N to throw said clutch into operative position, and mechanism communicating rotary movement between the main shaft C and the disk-driving mechanism in a determined ratio, whereby a desired number of revolutions are imparted to the shaft C for twisting the shank of the hook, after each operation of the wire-bending mechanism, substantially as described.

8. In a machine for forming hooks on wire bale-ties, the combination of the main shaft C, a clutch-coupling H for imparting intermittent rotation to said shaft, a cam-disk N operating the wire-bending mechanism through suitable connections, means actuated by the revolution of said cam-disk moving the clutch-coupling to operative position and holding it in operative position during a certain part of the revolution of said cam-disk, substantially as described.

9. In a machine for forming hooks on wire bale-ties, an automatically-operated clutch-coupling operating the cam-disk N and the main shaft C comprising a shaft, a cylindrical casing mounted on said shaft by means of a spline connection, a cut-out portion in the boring of said casing, a spring surrounding the shaft and lying in said cut-out portion, a suitable abutment on the shaft so as to keep said spring in place, a side flange on said casing having lateral projections, means loosely rotating on said shaft having corresponding projections, substantially as described.
